L. Conrad & Danck

UNITED STATES PATENT OFFICE.

ALEXANDER KONOFF, OF NEW YORK, N. Y., ASSIGNOR TO VOICES INCORPORATED, OF WILMINGTON, DELAWARE, A CORPORATION OF DELAWARE.

SOUNDING DEVICE FOR DOLLS AND OTHER TOYS.

Original application filed June 22, 1922, Serial No. 570,209. Divided and this application filed October 29, 1924. Serial No. 746,672.

The invention pertains more particularly to sounding or talking devices, so-called, for use in connection with dolls, and it resides in the novel sounding or talking device 5 hereinafter described and claimed, to be positioned within the body of a doll or other toy and which device will remain inactive when the doll is in one position and operate to emit a sound, as talking or crying, when 10 the doll is placed in another position.

One purpose of the invention is to provide a comparatively simple, durable, easily constructed and highly efficient sounding or talking device to be placed within the body 15 of a doll and which will, by preference, be capable of giving the well-known "ma-ma" or "pa-pa" sound when the doll is changed from one position to another.

The device of my invention comprises an 20 exterior box or casing, a tubular bellows located therein and secured at one end to one end thereof, a piston secured to the other or free end of the bellows and adapted of its own weight to collapse the bellows 25 when the casing is turned to one position and to elongate the bellows when the casing is turned to a reverse position, a central stationary shaft extending lengthwise of the casing and through the aforesaid piston and 30 serving as a guide therefor, a sound-box carried by said piston and having an aperture through which said shaft freely extends, and a reed secured in said head and opening into said sound-box, said shaft being 35 recessed or grooved annularly so that as the piston on the bellows is moving along said shaft and collapsing the bellows and driving the air therefrom through the reed, the outflow of air from the sound-box through 40 said aperture therein may be interrupted by those portions of the shaft at the sides of said annular grooves when said portions are respectively within said aperture and be free when the annular grooves in said 45 shaft coincide, respectively, with the aperture in the sound-box, this alternate interruption and release of the flow of air from the sound-box resulting in the reed efficiently giving distinct sounds or intonations of 50 the "ma-ma" or "pa-pa" character.

This application is a division of my co-

pending application Serial #570,209, sounding device for dolls and other toys.

The invention will be fully understood from the detailed description hereinafter 55 presented, reference being had to the accompanying drawings, in which:—

Fig. 1 is a central vertical section through a sounding device constructed in accordance 60 with and embodying my invention, the device being shown in initial position preparatory to being operated on being reversed in position.

Fig. 2 is a like view of the same shown 65 as having been reversed in position and the mechanism as having been operated.

Fig. 3 is a horizontal section through the same, taken on the dotted line 3—3 of Fig. 2.

Fig. 4 is a horizontal section through the same, taken on the dotted line 4—4 of Fig. 70 2, and

Fig. 5 is a perspective view of the same, 75 a portion of the covering of cheese-cloth or the like for the box or casing being shown as partly broken away.

In the drawings, 10 designates a cylindrical box or casing preferably formed of paste-board and having in its side walls a series of horizontal rows of apertures 11. At the top and bottom of the box or casing 80 10 I provide reinforcing disks 12, 13 respectively, of indurated fibre or other reasonably stiff material, and exterior to said disks 12, 13 and serving to hold the same in position, I provide the box or casing 10 with 85 caps 14, 15, which, with said disks, serve to close the ends of the box or casing 10. The disks 12, 13 add strength to the structure and are centrally apertured to receive reduced end portions 16, 17 formed on a 90 central stationary shaft 18 constituting one of the features of the sound producing mechanism and which becomes rigidly positioned between the disks 12, 13, the ends of said shaft adjacent to the reduced portions 16, 17 95 thereof being in abutting relation to the facing sides of said disks, as shown in Figs. 1 and 2.

The shaft 18 is annularly recessed or grooved, as at 19, 20, the groove 20 being 100 wider than the groove 19 and both of said grooves at their end portions being tapered

or conical, as at 21. Aside from the annular grooves 19, 20, the shaft 18 is a plain cylindrical shaft and is divided by the annular grooves 19, 20 into an elongated end section 22, a less elongated opposite end section 23 and an intermediate section 24, the section 24 being between the annular grooves 19, 20. Within one end of the box or casing 10 is secured a bellows 25, this bellows being 10 of flexible material and in the form of a tube or bag, one end of which is caught between the side flange of the cap 15 and the adjacent outer side surface of the box or casing 10, as indicated at 26, whereby the bellows 15 becomes at one end firmly secured in position. The opposite end of the bellows 25 is secured to a metal piston 27 which is in the form of a disk and extends across and rather snugly fills the transverse diameter 20 of the box or casing 10. The piston or head 27 is formed with an annular groove 28 and receives a wire ring around which the inner end of the bellows 25 is wrapped and whereby said end of the bellows becomes firmly 25 secured to the piston 27. In Fig. 1 I show the bellows 25 distended or elongated to its full extent by the pulling weight of the piston 27, while in Fig. 2 I illustrate the reverse position of the device and the bellows 30 25 as having collapsed under the pressing weight of said piston.

The piston 27 comprises a central sleeve portion 29 which fits, with reasonable clearance, the exterior portions of the shaft 18 and serves as an elongated guide for the piston 27 during its movements along said shaft. At its outer side the piston 27 is formed with a cylindrical flange 30 in whose outer end is rigidly seated a cap-disk 31 of indurated fibre or other rigid material having a central opening 32 of slightly greater diameter than that of the shaft 18, upon which it moves. The flange 30 and cap 31 create a sounding chamber 33. At 40 one side of the sleeve 29 the piston 27 contains a boring 34 within which, by means of a holder 35, is secured a reed 36 of ordinary construction, said reed at one end opening into the chamber 33.

50 The box or casing 10 has applied upon its exterior surface a layer of cheese-cloth 37, for the purpose of preventing the entrance of dust or the like through the apertures 11 formed in said box or casing. The cheese-cloth 37 is held in position and the caps 14, 55 15 are likewise secured in position by a coating of sealing wax or the like 38, applied over said caps and extending upon the adjacent edges of said cheese-cloth, as 60 illustrated in Figs. 1, 2 and 5.

The cap or disk 31 is formed with a venting opening 40.

When the box or casing with its enclosed mechanism is turned to the position shown 65 in Fig. 1, the weighted piston 27 slides

downwardly upon the shaft 18 and stretches out or extends the bellows 25 so that at such time said bellows is of cylindrical form closely adjacent to the inner sides of the box or casing 10. The movement of the 70 weighted head or piston 27 to the position illustrated in Fig. 1 causes the disk 31 to slide downwardly upon the section 23 of the shaft 18 and the sleeve 29 of said head to move downwardly upon the then upper end 75 of said shaft section 23 and over the annular groove 19 formed in said shaft, the section 24 of the shaft being within the sleeve 29 and the then upper end of said sleeve partly encompassing the annular 80 groove 20 formed in said shaft. When the head or piston 27 moves to the position shown in Fig. 1, the bellows or bag 25 becomes filled with air entering through the opening 40 and reed 36 and at times through 85 the hole 32 and around the shaft 18. It is the expulsion of the air from the bellows or bag 25 through the reed 36 which causes said reed to give forth its sound, and this sound is modified by the movement of the 90 piston 27 along the shaft 18, the expulsion of the air from the bellows or bag 25 and the sounding of the reed 36 taking place when the device is reversed so as to take the position shown in Fig. 2. When the device 95 is reversed in position so that the piston 27 is at the upper side of the bellows or bag 25, said piston will slide down on the shaft 18 and collapse the bellows or bag 25, as shown in Fig. 2, and thereby force the air 100 from within the bellows through the reed 36 and the opening 32 in the disk 31. The reed would make a prolonged sound in the absence of the annular grooves 19, 20 and shaft sections 23, 24, and in order to modify 105 the sound of the reed and cause it to produce the well-known "ma-ma" or "pa-pa" sounds, the weight 27 first carries the opening 32 of the disk 31 from over the shaft section 23, which substantially closes said 110 opening, and over the annular groove 19 which, not fitting the opening 32, permits the sound to escape through said opening. When, during the descent of the head 27, the opening 32 passes upon the shaft section 24, said opening becomes substantially 115 closed and said section 24 by choking said opening 32 effects a cessation of the sound of the reed. After the opening 32 in the disk 31, on the further descent of the head 27, passes from this shaft section 24 and upon the annular groove 20, the opening 32 again becomes free for the passage of air 120 from the bellows and the reed is permitted again to give forth or emit its sound. The 125 reed emits its sounds during the movement of the opening 32 in the disk 31 over the annular grooves 19, 20 in the shaft 18, the first sound, as "ma", taking place when the opening 32 leaves the shaft section 23 and 130

passes over the annular groove 19, and the second sound "ma", taking place upon the opening 32 of the disk 31 leaving the shaft section 24 and passing over the annular groove 20.

The sounds emitted by the reed 36 escape through the rows of perforations 11 in the box or casing 10, and I employ a considerable number of the openings 11 so that the sounds of the reed may freely escape, and as shown in Fig. 2, I have a row of the openings 11 along the line of the annular groove 19 in the shaft 18 and another row of said openings along the line of the annular groove 20 in said shaft, this disposition of the openings 11 serving to facilitate the escape of the sounds of the reed from within the box or casing.

In the present instance the shaft 18 has two side recesses or grooves 19, 20, and I make use of the two recesses or grooves for the purpose of securing two distinct spaced apart sounds from the reed, as "ma-ma", on each operation of the device. If the shaft 18 should only have one side recess or groove, as 19, the reed would only give one sound on each operation of the device, the duration of that sound depending on the width of the recess or groove. If the shaft 18 should be formed with three of the side recesses or grooves, the reed would give three distinct sounds on each operation of the device, one sound being emitted as the opening 32 passes each of said side recesses or openings.

For a proper interpretation of certain of the claims forming part hereof it is understood that the bellows present may be correctly considered to comprise opposite head parts connected together by the flexible tubular member 25, one of the heads being the part 27 which is slidably supported by the shaft or post 18, and the other head being the bottom wall parts as 13, 14, and 38 of the casing. The bottom wall parts 13, 14 and 38 comprise a closure for both the lower end of the bellows and the lower end of the casing. After the lower marginal portion of the bellows has been folded outwardly and upwardly about the lower end of the casing these closure parts are applied and serve to clinch and clamp the marginal portions of the bellows material against the material of the casing, and by the same means firmly hold themselves in position for properly supporting the shaft or post 18.

I have hereinbefore described the preferred embodiment of my invention but desire it to be understood that I do not confine the invention to all the details of form and construction shown and described since I am aware that many of these details may be

modified within the spirit and scope of my invention as defined in the appended claims.

Having thus described my invention, what I claim as new and desire to secure by Letters Patent is:—

1. In a sound producing device, a casing, sound producing means enclosed within said casing including a flexible bellows wall having one end edge thereof turned outwardly around one end of the casing wall, closures for the opposite ends of said casing each having an annular flange to extend around the casing wall, and the flange of one of said closures having clamping engagement with said outwardly turned end edge of the casing wall, said casing wall having openings therethrough for the emission of sound, a sheet of fabric material externally covering said casing wall and the sound emission apertures and extending at its ends upon the flanges of said closure members, and a sealing material completely enveloping each of the closure members and extending inwardly upon said fabric material beyond said flanges. 75

2. In a sound producing device, sound producing means, an enclosing casing therefor having a cylindrical body wall provided with sound emission apertures, a sheet of fabric material enveloping said casing wall and extending over the apertures therein to exclude dust from the interior of the casing, and means for effecting an air tight seal 90 of each end of the casing including means extending upon said fabric sheet and securing the same to the casing wall. 95

3. In a sound producing device, sound producing means, an enclosing casing therefor having a body wall provided with sound emission apertures, a tubular sheet of fabric material enveloping said casing wall and extending over the apertures therein to exclude dust from the interior of the casing, a closure disc for each end of the casing, and means for retaining said closure discs in applied position engaged upon the opposite ends of said tubular fabric sheet and securing the same to the casing wall. 100 105

4. In a sound producing device, a casing, closures for the opposite ends of said casing, a bellows within the casing having a flexible tubular wall one end edge of which is turned outwardly around one end of the casing wall, and an initially plastic imperious sealing medium enveloping the latter end of the casing and the closure therefor and extending inwardly beyond the outwardly turned edge of the bellows wall to provide an air tight seal between said closure, the end of the bellows wall and the casing wall. 115 120

In testimony whereof I affix my signature.
ALEXANDER KONOFF.
